UNITED STATES PATENT OFFICE

2,401,664

BOX

Irving Robins, Chicago, Ill., assignor of one-half
to Leonard Robins, Chicago, Ill.

Application February 8, 1945, Serial No. 576,791

1 Claim. (Cl. 229—52)

1

The invention relates to boxes and more particularly to handles for boxes to facilitate the carrying of boxes.

It is an object to provide a handle which may be readily applied and removed from a box so that the carrying of the box when necessary or the opening of the box may be readily accomplished.

It is a further object to provide a handle which at its ends is provided with a head adapted to be inserted through slots provided in the box free from distortion of the heads.

It is a still further object to provide a handle whose end heads may be inserted under an angle through slots in the box and which heads do not interfere with the content of the box and occupy a minimum space at the inner face of the slotted box wall.

With these and other important objects in view which will become apparent from a perusal of the invention, the latter comprises the means described in the specification, particularly pointed out in the claim forming a part thereof, and illustrated in the accompanying drawing, in which

Fig. 1 is a perspective view of a combined box and handle constructed in accordance with my invention.

Fig. 2 is an end view.

Fig. 3 is a section on the line 3—3 of Fig. 1.

Fig. 4 is a fragmentary view showing the enlarged slot in the box and the handle under angle ready for insertion in the slot.

Fig. 5 is a detail view of the handle.

Referring to the drawing, 10 generally designates the box which may be made of frangible or other material and is shown by way of example as having a rectangular cross section. The box has end walls 11 which have near the top an oblong slot 12, said slots being in horizontal alignment.

A similar slot 13 near the bottom of each end wall may be provided.

A handle 14 comprises an elongated band or strip and terminates at each end with an arrow head 15.

The slots 12 or 13 are preferably in the form

2

of a trapeze or quadrilateral and the diagonal length of said slots slightly exceeds the width of the arrow head 15 to thereby afford insertion of the arrow under an acute angle as shown in Fig. 4.

After insertion and the handle occupying normal position the arrow heads now on the inner face of the end wall are prevented from working through the slots 12 since the width of the arrow head exceeds the width of the slot.

The slots 12 and 13 serve as vent openings for the box.

The arrow heads may be easily inserted as they do not interfere with the contents of the box and not having been distorted while being inserted they lie flat against the inner face of the end walls.

If preferred the handle may be applied through the slots 13.

20 While the drawing shows one embodiment of the invention numerous changes and alterations may be made without departing from the spirit of the invention.

I, therefore, include all changes and modifications constituting departures within the scope of the invention as defined in the appended claim.

I claim:

25 For use with a packed box, an oblong quadrilateral open slot in each of the end walls of the box, a handle comprising a body portion and a tapering head at each end of the body portion, the length of the head being slightly less than the diagonal length of the slot and slightly greater in length than the length of the slot, and the head being insertable in an angular position through said tapering slot while contacting with the inner surface of said end wall and while out of engagement with the contents of the box and without distortion of the head, said head at its 30 inner end projecting laterally beyond the body portion of the handle and having a width greater than the width of the slot, whereby the handle 35 becomes anchored to the box when turned from said angular position to normal position for use.
